UNITED STATES PATENT OFFICE.

JOHN J. KENNEY, OF PITTSBURGH, PENNSYLVANIA, ASSIGNOR TO BEST ELECTRIC COMPANY, OF PITTSBURGH, PENNSYLVANIA, A CORPORATION OF DELAWARE.

SEPARABLE PLUG.

1,297,179.

Specification of Letters Patent. Patented Mar. 11, 1919.

Application filed August 7, 1916. Serial No. 113,508.

To all whom it may concern:

Be it known that I, JOHN J. KENNEY, a resident of Pittsburgh, in the county of Allegheny and State of Pennsylvania, have invented a new and useful Improvement in Separable Plugs, of which the following is a specification.

This invention relates to separable attachment plugs, such as are used for making 10 connections from a portable lamp, electric iron, or other device, to a lamp socket, or any similar source of current. The object of the invention is to provide a separable plug comprising the usual base member, 15 and a cap, which, when coupled together, are held securely, but which may be easily disengaged by an outward or lateral pull on the cap, without injury to the plug or detachment of the cords. A further object of 20 the invention is to provide a separable attachment plug whose members are held together by means of resilient contact members which can be readily freed from connection to each other when desired. A further 25 object of the invention is to provide a separable attachment plug the two parts of which may be easily engaged by direct longitudinal movement together, and easily disengaged by any movement from each other. 30 A further object is to furnish means for attaching the two parts of the separable plug together comprising spring contact members adapted to form conducting terminals, and also means for engaging the conducting 35 parts, and holding them under spring pressure. Further objects of the invention will appear hereinafter, and will be apparent to those familiar with such devices.

In the drawings, which illustrate an embodiment of the invention, Figure 1 is a vertical central section through the entire plug, the parts being in engaged position; Fig. 2 is an under view of the cap; Fig. 3 is an under view of the base; Fig. 4 is a partial vertical section on the line 4—4, Fig. 1; Fig. 5 is an end view of the threaded shell contact member.

The plug comprises the usual cap member 1, and base member 2. To the cap member is secured by means of screws 3 conducting metal plates 4, which carry binding posts 5 for the ordinary conductor wires. These plates are spaced apart sufficiently to be insulated from each other.

55 Clamped under the plates 4 are metal ter-

5 minal members 6, preferably made of a material having considerable resiliency, but being a good conducting medium. These spring members are extended downward in axial alinement with the central opening 7, 60 in the cap, which is adapted to receive the conductor cords, and are in the form of flat strips of metal, each having a terminal tongue 8 which is pressed into the form of an outwardly bent hump 9, as shown in 65 Fig. 1.

The base portion, which is made of any suitable insulating material, such as porcelain, glass, rubber, or composition, but preferably of a material which may be easily 70 molded, is of the proper shape and size to fit into the ordinary socket. It is formed with a central axial bore 10, and with two other openings, 11 and 12, extending longitudinally through the base, on diametric 75 sides of the central bore, preferably rectangular, and adapted to receive the spring members 6 extended downward therein from the cap. Fixed to the lower end of the base in a manner described below and extending 80 upwardly through the openings 11 and 12, are two spring contact members 13 and 14, which are made of flat metal strips, of substantially the same width as the members 6, and having their upper ends slotted, as 85 shown in Fig. 4, to form parallel projections 15, which are bent inward at their ends, as shown in Fig. 1. At the ends of the slots 16, the members are bent to form shoulders 17. 90

By this construction of the spring contact members, when the cap is forced into engagement with the base member the members 6 meet the ends of the members 13 and 14, at their inwardly inclined ends, and 95 ride thereupon, until the tongues 8, moving in the slots 16, reach the shoulders 17. Further pressure causes the humped tongues to be bent inward, and allows them to slip past the shoulders 17 and to spring outward and 100 so forms a resilient locking engagement of the tongue and slot, as will be obvious. By this means the cap and base are held securely together under normal conditions, but the cap may be readily released by overcoming the resilient spring engagement described. This may be done not only by a direct longitudinal withdrawing movement, but also by a lateral pull, causing the cap to rise on one edge as a fulcrum. The 110

5 springs are adapted to release by a pull from either side. This construction is particularly adapted for electric fixtures used on a dining table, etc., where the plug is frequently disconnected by merely giving the wires a pull, or by knocking it out of a floor socket with the foot. With the present arrangement this is readily done without danger of injury to the plug or of detaching 10 the conductor wires.

10 On the base 2 a metal threaded shell contact member 18 is mounted. This is pressed out of any suitable sheet metal, and is cup-shaped, to slip onto the end of the base. 15 The bottom is punched out, to form a central opening, as shown in Fig. 5. This opening is enlarged at one end, so as to give good clearance for passage of the conducting member 14 therethrough. The 20 other end of the opening is rectangular, and a portion of the metal punched out, in the form of a strip 19, is bent around the base into the opening 11, forming a clamp to surely hold the spring member 18, which 25 is bent around and under the base, all as shown in Fig. 1. The other terminal member 14, is extended beyond the base, and has its end clamped under the central terminal rivet 20. After the shell 18 is in position 30 on the base, an insulating disk 21 is placed over its end. This disk has an opening 22, through which the conductor 14 passes to make contact with the central rivet 20. It also has a central hole through 35 which the rivet 20 passes, and there may also be provided an additional insulating disk 23, and a central metal washer 24. All of these parts are held in position by the rivet 20, which extends through the axial 40 bore 10.

40 In the construction above described, the plug consists of a cap carrying the conducting terminals and binding posts, all in an integral form. The base has spring contact 45 members adapted to engage the conducting terminals of the cap, and to connect with an outer shell contact and a central terminal contact, as is usual in such plugs. All of the parts on the base are fixed in position 50 by a rivet or screw, and need never be dis-

assembled. The two parts of the plug are adapted to engage and to form the necessary contacts by a single longitudinal movement. The means provided are sufficient to give a strong locking action, and yet there 55 is no difficulty in separating the cap from the base by most any withdrawing movement. When the cap is removed the binding posts and conductor wires carried thereon are completely exposed, and in position 60 for adjustment or disconnection. The convenience and efficiency of construction will be apparent to those familiar with the art.

I claim:—

1. An attachment plug having a separable cap and base, terminals carried by one of said members, said terminals having a curved end tongue, contacts carried by the other member, said contacts having a notch in the end thereof, and an inclined end, 65 whereby said terminals and contacts engage and disengage by relative movement to lock the cap and base together.

2. An attachment plug having a separable cap and base, terminals carried by the 75 cap and contacts carried by the base, said terminals being formed of resilient metal and having a hump in the end thereof, said contacts being formed of resilient material and having a slotted offset portion at the 80 end thereof adapted to engage said hump, whereby the terminal and contact members engage to lock the cap and base together.

3. An attachment plug having a separable cap and base, terminals carried by the 85 cap and contact members carried by the base, said terminal members being formed with raised tongues in the ends thereof, and said contact members being formed with inclined slotted ends and an offset portion 90 at the end of the slot, adapted to engage said humps on the terminal members, whereby to lock the cap and base by engagement of the conducting members.

In testimony whereof I have hereunto set 95 my hand.

JOHN J. KENNEY.
